US00D978888S

(12) United States Design Patent (10) Patent No.: US D978,888 S
Ceniceroz (45) Date of Patent: * Feb. 21, 2023

(54) DISPLAY SCREEN OR PORTION THEREOF
WITH A GRAPHICAL USER INTERFACE

(71) Applicant: IGT, Las Vegas, NV (US)

(72) Inventor: David Ceniceroz, Reno, NV (US)

(73) Assignee: IGT, Las Vegas, NV (US)

() Term: 15 Years

(21) Appl. No.: 29/866,422

(22) Filed: Sep. 12, 2022

Related U.S. Application Data

(62) Division of application No. 29/743,409, filed on Jul. 21, 2020, now Pat. No. Des. 965,603.
